UNITED STATES PATENT OFFICE

2,442,144

STRAP HANGER

Max Rachlin, Flushing, N. Y.

Application July 29, 1947, Serial No. 764,472

1 Claim. (Cl. 248—48.1)

1

The present invention relates to improvements in gutter-hangers, that is, devices for supporting roof-gutters. The invention pertains more particularly to gutter-hangers including a bar portion adapted to extend transversely between the upper edges of the gutter and a roof strap pivotally connected thereto.

The main object of the invention is to provide a gutter-hanger of the type mentioned with improved means for pivotally connecting the roof strap to the bar portion whereby the possibility of the roof strap becoming disconnected or torn away from the bar portion is substantially eliminated.

A further object of the invention is to provide improved means of the aforementioned type comprising a slotted clip and a rivet or equivalent means for pivotally connecting the roof strap to the bar portion of the gutter-hanger, whereby the rivet or equivalent means functions primarily as a pivot only for the strap and the clip functions to transmit the weight of the gutter and contents to the strap.

Other and further objects of the invention will become apparent as the description proceeds, reference being made to the accompanying drawing forming a part of the present disclosure, wherein:

Fig. 1 is a side elevation of a gutter hanger constructed in accordance with my invention;

Fig. 2 is a top plan view thereof;

Fig. 3 is a side elevation of the hanger in the process of applying the same to a gutter, the latter being shown in cross-section, and the roof strap shown at substantially right angles to the bar portion whereby it lies entirely within the area defined by the edges of the gutter;

Fig. 4 is an elevation similar to Fig. 3, showing the hanger in position on a gutter; and

Fig. 5 is an enlarged sectional view taken on the line 5—5 of Fig. 1, looking in the direction of the arrows.

In gutter-hangers of the type to which the present invention relates it is desirable that the roof strap be pivotally connected to the bar portion of the hanger in order that the said strap may be positioned within the area defined by the edges of the gutter so as to minimize interference with the workmen or the building, while the gutter is handled to properly position the same relative to the roof of the building.

Previously, the roof strap has been pivotally connected to the bar portion of the hanger by means of a rivet, but this construction requires the use of a larger bar to offset the weakening

2

thereof by the rivet opening and in addition provides a very weak, ineffective and unsatisfactory connection. In riveting the strap to the bar portion, it frequently happens that the metal surrounding the rivet receiving hole in the strap, or the rivet receiving hole in the bar, or both, are weakened, and as a result the strap either pulls from the rivet, or the rivet pulls from the hole in the bar. Such defects require a relatively high percentage of replacements in gutter-hangers as previously constructed, and the present invention obviates these difficulties by the means presently to be described, whereby replacements of the gutter hangers for such reasons are practically eliminated.

Referring to the drawings, the numeral 1 indicates a roof gutter, the outer edge of which is provided with a bead 2, as usual in constructions of this type, while its inner edge 3 is plain. For supporting this gutter in proper relation to the roof of the building, there is provided a plurality of hangers, spaced apart a suitable distance, each of said hangers comprising a strap 4, which surrounds the gutter transversely, and a roof strap 5 attached to the strap 4 and adapted to be attached to the roof of the building. The strap 4 is preferably made of a single piece of sheet metal, and includes a rigid bar portion 6, preferably a channel bar, adapted to extend transversely between the upper edges of the gutter. On one end of this bar portion 6, an arched portion 7 is formed that is designed to be bent around the bead 2 of the gutter. This arched portion is initially of substantially semi-circular configuration, merging into a cradle portion 8, designed to underlie the gutter. The free end 9 of the cradle portion 8 is adapted to be engaged with a slot 10 in a substantially U-shaped bend 11 on the opposite end of the strap 4, said bend being in engagement with the plain edge of the gutter.

As illustrated most clearly in Fig. 5, the roof strap 5 is connected to the bar portion 6 of the strap 4 by means of a channel clip 12 engaging the end portion 13 thereof. The bottom edges 14 and 15 of the clip 12 are turned inwardly and upwardly to embrace the lower edges 16 and 17, respectively, of the bar 6 to securely clamp the roof strap 5 to the said bar. A pin or rivet 18 extends through an opening 19 in the clip 12, an opening 20 in the roof strap 5, and an opening 21 in the bar portion 6 to pivotally connect the strap 5 to the bar portion 6. The structure just described can be readily assembled since the bending of the lower edges of the clip may be

performed in the same machine simultaneously with the riveting.

To provide for pivotal movement of the strap 5, a slot 22 is provided in the clip 12 extending inwardly from an edge of one side wall thereof. The slot 22 is in alignment with the roof strap 5 and provides means whereby the said strap may be rotated to the out-of-the-way position illustrated in Figs. 3 and 4.

It is to be noted that the clip 12 functions to transmit all forces from the bar 6 to the roof strap 5, the rivet 18 merely functioning as a pivot for the said strap. Hence, the liability of the strap 5 to pull from its supporting rivet is eliminated, as is also the liability of the rivet to pull from the bar 6, while still permitting rotational movement of the said strap for the reasons above noted. In addition, it is unnecessary to increase the size of the bar to offset the rivet opening 21 therein since the clip 12 strengthens the bar to such an extent as to more than offset the loss in strength due to the said opening.

Although the present disclosure describes in detail the preferred form of my invention, it is to be understood that many changes may be made in the size and proportion of the various parts and details of construction as come within the scope of the appended claim, without depart-

ing from the spirit or sacrificing any of the advantages of the invention.

I claim:

5 In a gutter hanger including a rigid portion adapted to extend transversely between the upper edges of a gutter, and a roof strap, means connecting said roof strap to said rigid portion, said means including a clip embracing an end portion of said roof strap and said rigid portion, 10 pivot means for connecting said strap to said clip and rigid portion at said end portion of said roof strap, and a slot in one side wall of said clip in alignment with said strap for receiving the roof strap to provide for moving the same 15 to an out-of-the-way position while the gutter is handled to properly position the same relative to the roof of a building.

MAX RACHLIN.
